UNITED STATES PATENT OFFICE.

VALORUS S. WESTCOTT AND GEORGE B. ALLEN, OF PAWTUCKET, RHODE ISLAND.

SPINNING AND TWISTING SPINDLE.

No. 887,162.

Specification of Letters Patent.

Patented May 12, 1908.

Application filed July 10, 1906. Serial No. 325,440.

To all whom it may concern:

Be it known that we, VALORUS S. WESTCOTT and GEORGE B. ALLEN, citizens of the United States, and residing at Pawtucket, in the county of Providence and State of Rhode Island, have invented certain new and useful Improvements in Spinning and Twisting Spindles, of which the following is a specification.

10 The present invention relates to spinning and twisting spindles. In devices of this character the rotating spindle is stepped into a non-rotary bolster which is supported near its upper end and made smaller in diameter 15 along its length than the containing case, so that under inequalities of the yarn load on the bobbin carried by the spindle which tends to vibrate or gyrate the spindle, the latter will be allowed to find its own center of rotation.

Various means have heretofore been employed to cushion the spindle and confine it within certain limits so as to reduce or remove the liability of vibration and wear 25 when the spindle is slightly out of balance or using an untrue bobbin. The latest advance in the art prior to our invention, so far as we are aware, employs a spring which yieldingly holds the bolster in the position to 30 which the spindle may shift it. These means, however, have proved either inefficient for high speeds or are expensive to make.

The object of our invention is to provide a novel and peculiarly simple construction of 35 spindle of the gravity type whereby the spindle will center itself with promptness and certainty, and in which any undesirable movement due to an unbalanced load or other disturbing tendency will be effectively 40 controlled, and consequently the attainable rate of spindle rotation materially increased. This we accomplish by the employment of one or more annular members or tubes held in a fluid containing reservoir, said tubes being 45 disposed relatively to each other and to the bolster and bolster case as to provide a series of thin annular spaces for the fluid, forming thereby in a small space a comparatively large cushioning surface to counteract 50 the vibratory or other disturbing tendencies and at the same time allowing the bolster to yield gently under such force as may tend to move it laterally.

The invention will be understood by reference to the accompanying drawings in which 55 Figure 1 is a vertical longitudinal section

of one embodiment of our invention, certain of the parts being in elevation; Fig. 2 a vertical longitudinal section through the bolster case; the bolster, spindle and certain 60 other parts being in elevation; Figs. 3 and 4 are horizontal sections on the planes of the lines 3—3 and 4—4 of Fig. 1 respectively; Figs. 5, 6, 7, 8, 9 and 10 are longitudinal vertical sections to illustrate various modifications; and Fig. 11 a horizontal section showing corrugated tubes.

Similar reference numerals indicate similar parts in the several views.

Referring to the drawings the numeral 1 70 designates a metallic spindle of the usual type having a whirl 2. This spindle is stepped into a bolster 3. The bolster case comprises two sections 4 and 5, the lower part of the former being exteriorly screw 75 threaded to receive the latter. Section 5 is limited in its position by a shoulder 6 thereon abutting against the beveled face 7 of the upper section 4. A nut 8 engages the threaded section of the case and is adapted to 80 clamp the latter to the rail of the spinning frame in the usual manner. The section 4 of the case extends within the whirl 2 and the upper edge 9 thereof constitutes a seat for a shoulder 10 formed on the upper end of the 85 bolster 3. To prevent any rotary movement of the latter it is provided with a key 11 (see Fig. 3) engaging a groove 12 extending longitudinally of the inner wall of section 4 of the case. The case is bored to permit of a 90 slight lateral play of the bolster 3, and the latter is bored to a sufficient depth to provide a proper bearing for the rotating spindle. As shown in Fig. 1 the bolster is bored throughout its length the lower opening 95 thereof receiving and being closed by a depending pin 13 which projects for a substantial distance into the lower section 5 of the case. For a short distance above said pin 100 the walls of the bolster are constricted to provide a seat 14 for the lower end of spindle 1.

The detachable section 5 of the bolster case constitutes a fluid reservoir, the fluid being fed from the usual well 15 formed in the flange 16 of the section 4 of the case, 105 through ducts 17. In the construction illustrated in Fig. 1 the bottom of section 5 is tapped to receive the threaded head 18 of a cylindrical tube 19 which extends upwardly and surrounds the depending pin 13. Encircling the latter is a cylindrical tube 20 110 which is forced upon and depends from the

lower end of bolster 3 into the oil reservoir. Resting loosely upon the bottom of the reservoir is an outer cylindrical tube 21 which extends upwardly to encircle the tube 20. In practice the lengths of the tubes 19, 20 and 21 relatively to each other are substantially as shown in Fig. 1. These tubes may be of any suitable material, preferably metal, the walls of which are from one-sixty-fourth to one-thirty-second of an inch in thickness. They are spaced apart, and the inner one 19 from pin 13 to admit a thin film of fluid between the opposing walls. The fluid used by us is that known to the trade as "spindle" oil, although any other suitable material for cushioning and lubricating may be employed. Suitable ducts 22 are provided to admit oil to the spindle bearing in bolster 3.

In Fig. 5 the bolster 23 is not bored throughout its length as in Fig. 1, the lower part thereof being solid and formed with a narrowed portion 24 projecting into the reservoir of section 5 of the case. Secured to the body portion of the bolster 23 is a depending cylindrical tube 25 between which and the projecting end 24 of said bolster is a cylindrical tube 26. The latter is seated on a perforated wall 27 extending across the lower part of section 5 to provide a sediment chamber 28.

Fig. 6 illustrates an embodiment of the invention similar to that of Fig. 5 except that in the former the outer cylindrical tube 25 is omitted. The use of a single tube, while productive of satisfactory results, we believe to be not as efficient as the use of two or more tubes.

Fig. 7 illustrates still another method of disposing of the tubes. In this form the depending tube 25 is the same as that of Fig. 5. This projects downwardly between the two legs of a U-shaped piece, said legs 29 and 30 constituting in reality two tubes joined at their bases and resting on the bottom of the oil reservoir. In this instance a pin 31 is stepped into an opening in the bottom of section 5 of the case and serves as a lateral support for the inner member 30. The diameter of pin 32 which projects from the lower end of the bolster 33 is slightly less than that of pin 31 to provide an annular space between the former and the member 30.

Fig. 8 illustrates an embodiment of the invention in which the tubes 34, 35 and 36 are so disposed as to encircle the pin 37 depending from the bolster 33 into the oil reservoir. All these tubes are unattached and rest loosely upon the bottom of section 5 of the case.

In Fig. 9 the bolster case 38 is shown as made of a single casting instead of in sections as heretofore described. The disposition of the tubes 25 and 26 is substantially the same as illustrated in Fig. 5. A shouldered pin 39 is set into the lower end of bolster 3.

In Fig. 10 the bolster 40 is modified by having its lower end recessed for a substantial distance to constitute a tubular member 41. In this form two tubes 42 and 43 rest loosely upon the perforated plate 27, and extending into the space between said tubes is a tube 44 secured to bolster 40. A pin 45 is stepped into the bottom of section 5 of the case and projects upwardly into the tubular member 41.

Although we have shown the tubes as having plain surfaces they may be corrugated as shown in Fig. 11.

In all forms of our invention above described it will be observed that the bolster is freely suspended at its upper end and has free lateral play from its point of suspension. It results from this that any force acting on spindle 1 tending to disturb its condition of equilibrium is transmitted to the bolster and this force is cushioned by the mobile film of oil or other fluid interposed between the bolster and the next immediately encircling tube, and so to the film of fluid between the inner and the next encircling tube. The fluid has free access to the annular space between the tubes and its nature constitutes it an efficient cushioning agent to minimize the effects of the vibratory or gyratory movements of the spindle. By the employment of a series of concentrically disposed tubes the slightest movement imparted to the bolster by the spindle is instantly resisted by and distributed to and over the comparatively large surface area of the film of fluid interposed between contiguous tubes, the result being to reestablish the normal working high speed equilibrium of the spindle in a much more sensitive, rapid and easy manner than has heretofore been attained.

By means of our invention any tendency of the spindle to shift or move the bolster laterally in response to the movement of the former to confine its axis of rotation in line with the center of gravity when carrying an unbalanced load is immediately and automatically corrected, this being effected before such movement becomes detrimental to an extent sufficient to break the yarn or lift the bobbin from its seat.

In the foregoing specification we have referred to an oil chamber and to oil as the cushioning medium employed, but we do not limit ourselves to the employment of oil as any fluid of suitable characteristics may be used.

We consider our invention in effect to be a laminated fluid spring cushion and believe ourselves the first to produce such a device. We desire to claim it broadly without limiting ourselves to the exact structures herein shown.

What we claim and desire to secure by Letters Patent is:—

1. In a device of the character described

the combination of a bolster case having a fluid containing reservoir, a bolster freely suspended at its upper end in said case, said bolster having free lateral play from its point 5 of suspension and extending into said reservoir, a spindle supported in said bolster, and a plurality of concentric tubes disposed in said reservoir and encircling the lower end of the bolster to form thin mobile cushioning 10 walls for the purpose described, one of said tubes being secured to and depending from the bolster.

2. In a device of the character described the combination of a bolster case having a 15 fluid-containing reservoir, a bolster freely suspended in said case and extending into said reservoir, a spindle supported in said bolster, and a plurality of annular members disposed in said reservoir encircling the lower 20 end of the bolster to form thin mobile cushion-

ioning walls for the purpose described, one of said annular members being secured to and depending from the bolster.

3. In a device of the character described the combination of a bolster case having a 25 fluid-containing reservoir, a bolster freely suspended in said case and extending into said reservoir, a spindle supported in said reservoir, and a plurality of annular members disposed in said case to form thin mobile 30 cushioning walls, the lower end of the bolster constituting one of said members.

In testimony whereof we have hereunto signed our names in the presence of two subscribing witnesses.

VALORUS S. WESTCOTT.
GEORGE B. ALLEN.
